US00D707847S

(12) **United States Design Patent**
Motadel et al.

(10) **Patent No.:** **US D707,847 S**
(45) **Date of Patent:** **** Jun. 24, 2014**

(54) **ANTI-STATIC PIPETTE TIP TRAY ASSEMBLY**

(71) Applicant: **Biotix, Inc.**, San Diego, CA (US)

(72) Inventors: **Arta Motadel**, San Diego, CA (US);
Scott Edward Curry, San Diego, CA (US)

(73) Assignee: **Biotix, Inc.**, San Diego, CA (US)

(**) Term: **14 Years**

(21) Appl. No.: **29/445,143**

(22) Filed: **Feb. 7, 2013**

Related U.S. Application Data

(62) Division of application No. 29/354,397, filed on Jan. 22, 2010, now Pat. No. Des. 679,025.

(57) **CLAIM**

The ornamental design for anti-static pipette tip tray assembly, as shown and described.

DESCRIPTION

FIG. 1 is a perspective view of an anti-static pipette tip tray assembly with a side-mounted discharge tab;

FIG. 2 is a back side view thereof;

FIG. 3 is a front side view thereof;

FIG. 4 is a cross sectional view thereof taken along lines 4-4 of FIG. 1;

FIG. 5 is an enlarged partial view thereof taken along line 5 of FIG. 4;

FIG. 6 is a right side view thereof;

FIG. 7 is a left side view thereof;

FIG. 8 is a top view thereof;

FIG. 9 is a bottom view thereof;

FIG. 10 is a top perspective view of a conductive pillow with a side-mounted discharge tab shown separately for clarity of illustration;

FIG. 11 is a front side view thereof;

FIG. 12 is a back side view thereof;

FIG. 13 is a left side view thereof;

FIG. 14 is a right side view thereof;

FIG. 15 is a top view thereof; and,

FIG. 16 is a bottom view thereof.

The broken lines illustrate portions the anti-static pipette tip tray assembly that form no part of the claim.
